UNITED STATES PATENT OFFICE

JULIUS JONAS, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

MERCURY VAPOR RECTIFIER

Application filed February 2, 1929, Serial No. 337,069, and in Germany February 23, 1928.

It has already been proposed to feed anodes of the same phase and working in parallel and belonging to one or more rectifiers over a transformer, common to them all, 5 which has several separate secondary winding parts co-ordinated to the separate anodes, which are evenly distributed over the primary winding. This arrangement has the object of forcing the anodes to take up 10 equal amounts of current. If the anodes be furnished with grids or arc guides, it may occur that the voltage drop between the separate parallel connected anodes and the cathode will be large. Through the grids, 15 potential space charges are produced which block the passage of current to a greater or less extent and may even entirely prevent it. The grid potentials, however, are by no means a fixed quantity and it is found that, 20 with very heavy current strengths, the grids of parallel connected anodes become charged very unequally, so that the originally equal distribution of current is considerably disturbed.

25 According to the present invention this disadvantage is overcome by the grids or arc guides of parallel connected anodes being coupled electrically, that is to say, the said arc guides or grids are conductively 30 connected. Where the grids are mounted in the guides so as to be insulated from them, the grids and the guides can each be conductively connected up separately. When there are a number of grids superposed over 35 one another in stories, the grids of the same story may be conductively connected, or the grids of different stories may be connected cross-wise. Even with controlled grids it is preferable to connect the grids of parallel 40 connected anodes conductively and to control them from a common voltage.

One embodiment of the invention is illustrated in the drawing in which reference character *a* generally indicates a rectifier of the metallic vapor type having a cathode *b* and a plurality of parallel operating anodes *c₁*, *c₂*, *d₁*, *d₂* connected with a transformer indicated generally at *e*. The transformer includes a primary winding *f* and a secondary winding divided into a plurality of por-

tions *g₁*, *g₂*, . . . *g_s* arranged in a uniform manner over the primary winding *f*. *h* indicates the usual movable ignition anode and *m*, *n* indicates the usual excitation anodes. The ignition and excitation anode connections are not shown to avoid unnecessary complication in the drawing. 55

Each of the anodes *c₁*, *c₂*, *d₁*, *d₂* is partially enclosed in an arc guide *h*. The arc guides of parallel operating anodes are conductively 60 connected and are provided with grids *i₁*, *i₂* likewise conductively connected. It will be seen from the drawing that the grids and the arc guides of the several groups of parallel operating anodes are conductively connected but it is to be understood that the grids may be insulated from the arc guides and that the grids may be separately conductively connected and that the arc guides may be separately conductively connected. 65

Although the preferred embodiment of the present invention only has been illustrated and described it will be apparent from the description and from the drawing that various changes may be made therein without departing from the spirit of the specification or from the scope of the appended claims. 70

What I claim is:

1. In means for obtaining an equal load division in an electric current rectifying system, a rectifier of the metallic vapor type, a plurality of anodes within said rectifier, said anodes being arranged in groups for parallel operation, a cathode within said rectifier, arc guides partially inclosing said anodes, grids arranged within said guides adjacent said anodes, the grids of parallel groups of said anodes being electrically connected, and a transformer including a primary winding and a secondary winding divided into a plurality of portions uniformly distributed over the primary winding. 80

2. In means for obtaining an equal load division in an electric current rectifying system, a rectifier of the metallic vapor type, a plurality of anodes within said rectifier, said anodes being arranged in groups for parallel operation, a cathode within said rectifier, arc guides partially inclosing said anodes, the guides of parallel operating 85

groups of said anodes being electrically connected, grids arranged within said guides adjacent said anodes, the grids of parallel groups of said anodes being electrically connected, and a transformer including a primary winding and a secondary winding divided into a plurality of portions uniformly distributed over the primary winding.

3. In means for obtaining an equal load division in an electric current rectifying system, a rectifier of the metallic vapor type, a plurality of anodes within said rectifier, said anodes being arranged in groups for parallel operation, a cathode within said rectifier, arc guides partially inclosing said anodes, grids arranged in insulated relation within said guides adjacent said anodes, said guides and said grids of parallel operating groups of said anodes being electrically connected, and a transformer including a primary winding and a secondary winding divided into a plurality of portions.

4. In means for obtaining an equal load division in an electric current rectifying system, a rectifier of the metallic vapor type, a plurality of anodes within said rectifier, said anodes being arranged in groups for parallel operation, a cathode within said rectifier, arc guides partially inclosing said anodes, a plurality of grids arranged within each of said guides, the grids in the same story in said guides being electrically connected, and a transformer including a primary winding and a secondary winding divided into a plurality of portions.

In testimony whereof I have hereunto subscribed my name this 22nd day of January A. D. 1929.

JULIUS JONAS.
